COMBINED LAMP HOLDER AND SWIVEL MOUNT THEREFOR

Leonard Atkin, Springfield, N.J., assignor to Stone Manufacturing Co., a corporation of New Jersey

Application August 25, 1959, Serial No. 57,302

Term of patent 14 years

(Cl. D48—20)

I claim:

The ornamental design for a combined lamp holder and swivel mount therefor, substantially as shown.
